HOODED WALL BRACKET

David K. Walz, Doraville, Ga., assignor to Lithonia Lighting, Inc., Conyers, Ga., a corporation of Georgia

Filed Oct. 1, 1965, Ser. No. 87,275

Term of patent 14 years

(Cl. D48—4)

FIG. 1

FIG. 2

FIG. 3

FIG. 4

FIG. 1 is a perspective view of a light fixture embodying the new design;

FIG. 2 is a side elevation view thereof;

FIG. 3 is a front elevation view thereof;

FIG. 4 is a top plan view thereof.

The broken line showing of a lamp globe in FIG. 1 is for illustrative purposes only.

I claim:

The ornamental design for a hooded wall bracket, substantially as shown and described.
